[57] CLAIM

The ornamental design for a children's clock, as shown.

DESCRIPTION

FIG. 1 is a perspective view of the children's clock

showing my design, which has moveable clock hands and twelve cubes placed in openings;

FIG. 2 is an elevational face view of the children's clock of FIG. 1;

FIG. 3 is a bottom plan view of FIG. 1;

FIG. 4 is an upper end view of FIG. 1;

FIG. 5 is a right side view of FIG. 1;

FIG. 6 is a cross-sectional view taken along the line 6—6 of FIG. 2;

FIG. 7 is an elevational face view of the children's clock as in FIG. 2 with the cubes repositioned with another side facing the viewer;

FIG. 8 is an elevational face view of the same children's clock as in FIG. 2 with the cubes turned in the openings with still another side facing the viewer;

FIG. 9 is an elevational face view of the children's clock as in FIG. 2 with yet another side of the cubes facing the viewer;

FIG. 10 is an elevational face view of the children's clock as in FIG. 2 with yet another face of the cubes facing the viewer; and

FIG. 11 is an elevational face view of the children's clock as in FIG. 2 broken away in part, with one cube removed from one of the openings and showing a perspective view of this cube and with the other cubes tilted in the openings.
